UNITED STATES PATENT OFFICE.

BENJAMIN F. BAIN, OF PITTSBURGH, PENNSYLVANIA.

MECHANICAL TOY.

1,244,456.

Specification of Letters Patent. Patented Oct. 30, 1917.

Application filed April 9, 1917. Serial No. 160,867.

To all whom it may concern:

Be it known that I, BENJAMIN F. BAIN, a resident of Pittsburgh, in the county of Allegheny and State of Pennsylvania, have 5 invented a new and useful Improvement in Mechanical Toys, of which the following is a specification.

This invention relates to automatic toys and particularly to such toys operated by 10 the weight of a load, and of a counter-weight. The invention is an improvement upon the toy shown and described in my prior Patent No. 1,192,031, dated July 25, 1916.

15 The swinging bucket described in said prior patent consists of a tilting discharge receptacle, and it is filled from a main hopper, while held in load receiving position by a positive latch mechanism. That construction requires a distinct element for retaining the bucket in position for a material period of time while it is receiving a load, an adjustable member for releasing the bucket upon receipt of a predetermined 25 amount of load, and other parts not necessary in the present invention. Furthermore, the prior construction requires a nice adjustment of parts not found in the present case, and the mechanism may be rendered inoperative by a number of causes, as by the 30 formation of rust on the latch member, or the distortion thereof, due to such handling as these devices must necessarily receive. The present invention is designed to avoid 35 entirely this latching feature, and also to secure a more rapid and more continuous actuation of the movable parts.

The object of this invention is to improve 40 the construction and operation of such toys and to provide a device having a fewer number of parts, and a more simple method of control than that set forth in said prior patent. The device simulates the movement of a sand bucket and the operation of 45 a swinging crane. The present form can be constructed at a lower cost, with simpler parts than those heretofore manufactured. A further object is to construct the toy so 50 that it will be continuous in operation, in which the swinging of the crane backward and forward will be at more frequent intervals, and in which the charging of a load into the swinging bucket will be more rapid than in the prior device. Particularly it is 55 designed to do away with the necessity of

any latch, or other mechanical part, used to lock the swinging bucket in position during the load receiving interval. This is accomplished by providing a different form of valve in the storage hopper; a larger opening therefrom to the load transporting receptacle; a different form of load receiving and transporting member, *i.e.*, a non-tilting bucket having a valve in the bottom; and differently operating discharge means for 60 the bucket—all as more fully described below. Except in the differences above noted, the operation of this toy is similar to that set forth in my prior patent referred to.

Referring to the drawings, which represent one embodiment of the invention, Figure 1 is a front elevation showing the swinging bucket in load receiving position; Fig. 2 is a similar view showing the bucket in load discharging position; Fig. 3 is a plan view, 70 the bucket being in load receiving position, the storage hopper and manikin being omitted, and the position of the hopper being indicated by a dotted line; Fig. 4 is an elevation and partial section on an enlarged 75 scale showing the mechanism for controlling or producing the motion of the bucket carrying arm, the parts being shown as situated in the load receiving position of the bucket; Fig. 5 is a horizontal section on the 80 line 5—5 of Fig. 4; Fig. 6 is a partial side elevation of the storage hopper and its outlet valve, the latter being in closed position; Fig. 7 is similar to Fig. 6 but with the valve 85 open; and Figs. 8 and 9 show a modified 90 form of storage hopper and load-measuring device.

The toy comprises a base 1, which is preferably in the form of a shallow tray provided with upwardly extending ears 2 95 punched from the bottom thereof, and having holes therein to receive the bent ends 3 of vertical supporting members 4, which support a load storage reservoir in the form of a conical hopper 5 which is fixed to the 100 supports by any suitable means, such as by rivets 6. These supports are rigidly connected near their middle point by a cross bar 7 to which in turn is connected an upright member 8 having its lower end hooked 105 into a side of the tray 1.

At the other end of the tray a frame member is provided in the form of an inverted U-shaped metal strip, having its upright portions 9 attached at the lower ends 110

to ears 10 on said tray. This engagement is secured by means of pins or rivets 11. The upper part of this U-member forms a horizontal supporting member across the tray and carries the movable crane later described. To the middle point of this horizontal portion is attached a vertical spindle or shaft 13 having a pointed end 14, forming a vertical axis about which the bucket-carrying arm swings, as will be more fully described below. Between a collar 15 on this spindle, and the supporting member 12, is clamped by means of riveted head 15^a, a sheet metal horizontal gear member 16, which lies flat upon the upper side of the horizontal support, and is rigid therewith. This gear member is provided with a series of vertically extending teeth 17, arranged in an arc about the axis of the spindle 13. The bucket-carrying arm consists of two metal strips 17 riveted together at each end and spread apart at their middle portions. At one end these members carry a counter-weight 18, while at the other they are joined to a terminal metal strip 19, which is riveted to the side of bucket 20. The middle portions of the strip 17 are provided with trunnions 21 which fit into openings in a small metal frame member 22, which rests on the point 14 at the upper end of spindle 13, the opposite ends of said frame being bent to form parallel horizontal ears 23 having openings to engage the spindle 13, as shown at the top of Fig. 4. This frame, and the bucket-carrying arm attached thereto, are readily mounted and dismounted from said spindle by merely slipping the ears over the spindle to the position shown in Fig. 4. When so arranged the frame 22 and the swinging bucket arm carried thereby are free to turn in a horizontal plane around the spindle 13 as an axis, and the bucket arm while swinging in a horizontal direction, is also capable of turning in a vertical plane around the trunnions 21 as an axis. By this means the bucket may have substantially a helical movement. That is, it has a swinging movement around a vertical axis, and simultaneously an up-and-down movement about the axis formed by trunnions 21. The component helical movement, in a definite path, is produced by the co-operation of the gear members shown, connecting the swinging arm and the fixed support for said arm. This mechanism comprises the stationary gear member 16 above referred to, the vertical teeth 17 of which intermesh with horizontally extending teeth 24, on the lower curved edge of a co-operating gear member 25, which is formed of a sheet metal plate rigidly attached to one of the strips 17 of the bucket-carrying arm. The relation of the gear members 16 and 25 is such that when the bucket-carrying arm 17 is tilted about its

trunnions 21 by either a load in the bucket or by the counterweight 18, the gear 25 is caused to roll around the stationary gear 16, and thus turn the frame 22 and the bucket-carrying arm thereon around the vertical spindle 13 as an axis. This is a simple arrangement of parts, entirely efficient for the purpose in view, and the shape of the members is such as to largely protect the gear teeth, so that injury thereto is not probable. The gear member 25 being a thin metal sheet which could easily be bent out of its proper plane, is provided with an arcuate slot 26 struck around the trunnion 21 as a center. A pin 27 is riveted in the member 22 and has a body projecting outwardly from said plane member and a head 28 lying on the outside of the slot 26, as shown in Fig. 2. This pin and slot connection strengthens the device, and renders its operation more certain, but is otherwise not essential.

Carried between one of the supports 9, and the upright 8 is a horizontal bar 29, to which is riveted a U-shaped metal plate 30 having horizontally extending ends 31 with holes 32 through the middle portion thereof. A manikin 33 is fixed to a metal plate 34 which has riveted thereto a pin 35, adapted to pass downward through the holes 32, leaving the manikin free to rotate with said pin as an axis. A cord 36 is attached to an arm 37 of the manikin at one end, and at the other to one end of a weight member 38 which is riveted onto a depending valve or gate 39 which controls the open bottom of bucket 20.

This bucket is attached to terminal 19 of the swinging member above described, and is of hopper shape, with a flaring mouth-piece 41. The entire bottom of this bucket is open, but normally is closed by the gate 39 which is in the form of a U-shaped sheet metal member having vertical wings 42 extending upward to a pin 43 fixed in the side of the bucket, so that the valve is free to swing on the pin as an axis. At the rear end, this gate valve is turned upward to form a wall 44, to prevent escape of material from the rear side. The weight member 38 fixed on the bottom of the valve, or gate, extends rearwardly a considerable distance, forming a counterweight holding the valve normally shut, with its top pressed against the bottom of bucket 20, at the forward edge, as shown in Fig. 1, the escape of material from the rear being prevented by the upturned edge or wall 44.

The storage hopper 5 has an outlet 45 at its lower end of large area compared to the size of the bucket to be filled and this opening is controlled by a swinging gate valve 47, which is of substantially the same form as the valve 39 controlling the bottom of the bucket. That is, it has a slanting bottom

47, with upwardly extending wings 48 having holes therein engaging a pin 49 fixed in the wall of hopper 5, and forming an axis about which the valve swings. The gate 5 has a raised edge at the rear forming a wall 50, and a depending arm 51, as shown in Fig. 6. This arm is used in coöperation with the swinging bucket to open the valve. It also acts as a counterweight, assisting in the quick and complete closure of the valve. By this construction the opening 45 in the bottom of hopper 5 is quickly opened completely, and as readily entirely closed by the swinging of the above described gate valve, 10 actuated by arrival and departure of the bucket.

The operation of the device is as follows:—The hopper 5 is filled with sand, or any other heavy, easily flowing dry substance. Escape therefrom is prevented by the valve 47, which is kept normally in closed position, as shown in Fig. 6. After the reservoir is filled, the swinging bucket-carrying arm 17 is released from lowermost position, and by the force of counterweight 18 swings around and upwardly to load-receiving position, the flared inner edge 41 of the bucket striking the depending arm 51 of the reservoir valve, and by the impact moving 25 it quickly and completely to the left to the position shown in Figs. 1 and 7, allowing material in the hopper to flow freely therefrom into the bucket 40. The size of the bucket is so determined with regard to the 30 counterweight 18 and the weight of material used to operate the toy that before the bucket is overfilled sufficient load will be contained therein to overcome the effect of the counterweight and cause the arm 17 to 35 swing outward and downward by gravity of the load. As this takes place the valve 47 controlling the main hopper follows the departing bucket, closing the outlet from the hopper so that no material escapes except 40 into the bucket, which thereupon swings outward and downward to the position shown in Fig. 2. The length of cord 36 is so adjusted that when the bucket arrives over receptacle 51, the gate 39 is pulled back into 45 the position shown in Fig. 2, allowing the entire contents of the bucket to be immediately discharged into said receptacle. Whereupon the counterweight which is of the proper weight to operate the crane upward when the bucket is empty, causes the 50 arm to swing in reverse direction to load-receiving position. The counterweight is so adjusted that there is sufficient momentum, or impact, at the end of this reverse swing 55 to actuate the controlling valve of the hopper so that a load is immediately discharged therefrom through the large opening 45 into the bucket, and the direction of movement of the latter receptacle changes without appreciable delay, swinging backward to dis-

charging position, where the load is removed also without delay, and the operation continues until the main reservoir is emptied.

By this construction it will be observed that the arm swings continuously and laterally from loading to unloading position, receiving a load instantly upon arrival at the hopper, and discharging it instantly upon arrival at the lower limit of its travel. The particular forms of valves provided in 70 the hopper and in the bucket avoid the necessity for any mechanical locks to hold them in open position for discharging material, and render their closing quick and certain.

In my copending application, Serial No. 144,789, filed January 24, 1917, a toy is described in which a car on an inclined track is operated by a load discharged from a hopper, as in this case. One feature of that 80 invention is the use of a supplementary load-measuring hopper, which is filled from an outlet of comparatively small area while the car is carrying a load to a distance and there discharging it. This supplementary measuring hopper is designed to just hold a load for the transporting member, and it is controlled at the bottom by a gate valve adapted to discharge the entire measured load into the car upon its arrival under the main storage reservoir. This form of load delivery 85 mechanism may be applied to the crane mechanism of the present case, by using the supplementary hopper as shown in Figs. 8 and 9. A partial side elevation is shown, 90 Fig. 8 having the valve in closed position, and Fig. 9 in open position. This valve is the same as that shown in Figs. 6 and 7, the difference being only in the use of the supplementary measuring receptacle 5, and a 95 more restricted outlet 45^a from main hopper 5. For fuller details of operation of this device reference is made to my copending application.

Furthermore, it will be apparent that the 100 particular form of valve and load-delivery means shown in Figs. 1 to 7 herein, may be applied to the hopper of my said copending application, so that the car will receive its load directly from the main hopper upon 105 arrival at the top of the track, as in the case of the bucket, as first described hereinabove.

I claim:—

1. In an automatic toy comprising a load-storing hopper having an outlet from the 110 bottom thereof, a movable member adapted to receive an operative load from the hopper and to discharge it at a distance therefrom, the combination of a valve controlling the outlet from the hopper, said outlet being of large area compared to the movable load-carrying member, and means extending across the path of travel of the transporting member adapted to entirely open the valve 115 upon arrival of the transporting member be- 120

125 130

- neath the outlet from the hopper, the outlet being of such size as to immediately discharge an operative load into the transporting member.
- 5 2. In an automatic toy comprising a load-storing hopper and a non-tilting movable member adapted to receive an operative load from the hopper and to transport and discharge said load at a distance, the combination of an outlet from said hopper of large area compared to the size of the load-carrying member, a valve controlling said outlet, means to completely open said valve immediately upon arrival of the transporting member beneath the hopper, so as to deliver at once an operative load to the transporting member, and means to close the valve by removal of the transporting member from beneath the hopper.
- 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810
- bottom of the bucket, a weighted lever arm tending to close the bucket valve, and a cord adapted to open the bucket valve upon arrival of the bucket at a predetermined limit of travel.
6. In an automatic toy, the combination with a storage hopper and a movable receptacle adapted to traverse immediately underneath said hopper to receive a load therefrom and to discharge said load at a distance, of a valve controlling a discharge opening from said hopper, and means operated by the movable receptacle on its arrival underneath the hopper for opening said valve, said discharge opening from the hopper and said valve being arranged to supply a complete operative load to said receptacle during its traverse across and back underneath said discharge opening.
7. In an automatic toy, the combination with a storage hopper and a laterally movable receptacle adapted to receive an operative load from said hopper and to discharge it at a distance therefrom, of a valve controlling a discharge from said hopper, and means for opening the valve by the movable receptacle upon its arrival underneath said discharge means, said valve and said discharge means being arranged to supply to the movable receptacle a complete operative load during its traverse across and back underneath the discharge means.
8. An automatic toy, comprising a load-storing hopper having a comparatively large outlet port in the bottom thereof, a valve controlling said outlet and having a depending arm attached to the bottom thereof, a swinging pivotally mounted arm having a bucket of small size compared to the outlet from the storage hopper at one end thereof, a counterweight heavier than the empty bucket at the other end, a valve controlling the bottom of the bucket and having a depending counterweight for holding said valve normally closed, and a cord attached to the bucket valve whereby to discharge the load being transported upon arrival of the bucket at a predetermined point, substantially as described.
- In testimony whereof, I have hereunto set my hand.

BENJAMIN F. BAIN.
